UNITED STATES PATENT OFFICE.

WALTER ROBERT WULFECK, OF CINCINNATI, OHIO.

GAS-BURNER.

969,021.

Specification of Letters Patent. Patented Aug. 30, 1910.

Application filed March 31, 1910. Serial No. 552,571.

To all whom it may concern:

Be it known that I, WALTER ROBERT WULFECK, a citizen of the United States, residing at Cincinnati, in the county of Hamilton and State of Ohio, have invented new and useful Improvements in Gas-Burners, of which the following is a specification.

This invention relates to improvements in gas burners such as are employed with 10 cooking stoves, hot air furnaces, steam and hot water boilers and has for its object the provision of a burner consuming a mixture of gas and air and so constructed that the flame will be directed downward and onto 15 the parts to be heated.

Another object is the provision of a burner having a continuous combustion opening, whereby a solid wall of flame will be produced when the gas flowing through 20 the said opening is ignited.

With these and other objects in view, which will more fully hereinafter appear, the present invention consists in certain 25 novel details of construction and arrangement of parts, hereinafter fully described, illustrated in the accompanying drawings and more particularly pointed out in the appended claims; it being understood that various changes in the form, proportion, 30 size, and minor details of the device may be made, within the scope of the appended claims, without departing from the spirit or sacrificing any of the advantages of the invention.

35 In the accompanying drawings, forming a part of the specification;—Figure 1 is a side elevation of the device. Fig. 2 is a plan view of the same. Fig. 3 is a vertical section taken on the line 3—3 of Fig. 2.

40 Similar numerals of reference are employed to designate corresponding parts throughout.

The body of the burner is designated by the numeral 5 and while I have shown the 45 same to be annular in contour it must be understood that I am not to be limited to this specific shape, since it will be readily understood, from what will appear later, how the body could be oblong or in fact 50 formed to any shape without departing from

the spirit or sacrificing any of the advantages of the invention.

The body 5 is preferably formed of a single piece of metal and may be cast or otherwise formed to the shape specified. As 55 shown in the drawings the burner is a tubular structure formed into an annulus and on its outer side and at the juncture of its upper and lower outer segments is split, such split extending entirely around the burner, 60 whereby a combustion opening 6 is provided the opposite sides of which are designated by the numerals 7 and 8. The upper side 7 is extended beyond the side 8 and directed downwardly and over the side 8, as shown in 65 Fig. 3 with its inner surface spaced from the adjacent surface of the side 8. With this construction it will be manifest that the overlapping side 7 will act as a deflector for the flame in the opening 6, whereby the flame 70 nearest the opening will be directed downwardly and onto the parts to be heated.

The pipe which supplies the mixture of air and gas to the burner is designated by the numeral 9, having one end flared to receive the gas supply pipe 10, the said flared end and pipe 9 being greater than the diameter of the gas supply pipe so that the gas passing through the latter will be mixed with the air passing through the flared end 75 of the pipe 9. The pipe 9 terminates at the medial portion of a horizontal tubular extension 11, the opposite ends of which are tapped into the body of the burner at diametrically opposite points, as clearly shown 80 in Fig. 3.

With this construction it will be manifest that a mixture of air and gas passing through the tubular extension 11 will enter the burner at opposite points and exit 90 through the combustion opening 6 at which it may be ignited and owing to the continuous opening 6 a solid wall of flame directed in a downward extension will be produced.

From the foregoing, it is evident that I 95 have provided a device which is comparatively simple in structure, and inexpensive in manufacture, embodying few parts and these so arranged that the danger of derangement will be reduced to a minimum. 100

I claim:—

1. A burner comprising a tubular body annular in contour and split at the juncture of its upper and lower outer segments, the edges of said split portions overlapping and spaced, for the purposes described.
2. A burner comprising a tubular body annular in contour and split continuously at the juncture of its upper and lower outer

segments, the upper edge of said split portion overlapping and spaced from the lower side, for the purposes described.

In testimony whereof I affix my signature in presence of two witnesses.

WALTER ROBERT WULFECK.
